UNITED STATES PATENT OFFICE.

JACKSON L. ROY, OF DE QUEEN, ARKANSAS.

CYCLONE-PROTECTOR.

1,275,476.

Specification of Letters Patent. Patented Aug. 13, 1918.

Application filed June 12, 1917. Serial No. 174,338.

To all whom it may concern:

Be it known that I, JACKSON L. ROY, a citizen of the United States of America, residing at De Queen, in the county of Sevier and State of Arkansas, have invented new and useful Improvements in Cyclone-Protectors, of which the following is a specification.

This invention comprehends improvements in cyclone protectors and aims to provide a box like structure which will afford shelter for a person or persons during a cyclonic disturbance.

Another and more specific object of the invention is to provide such a structure having walls formed of super-imposed layers of material each layer comprising a plurality of strips, said structure being provided with doors at each end and having a seat along one side.

A further object of the invention is to provide a cyclone protector with bumpers of sufficient strength and rigidity to cause the walls to withstand considerable pressure, and which protector will be in no danger of collapsing when thrown violently in contact with an obstruction.

With these and other objects in view as will become apparent as the description proceeds, the invention consists in certain novel features of construction, combination and arrangement of parts as will be hereinafter fully set forth, illustrated and claimed.

In the drawings:—

Fig. 1 is a perspective view of the cyclone protector,

Fig. 2 is a vertical sectional view through the protector,

Fig. 3 is a horizontal sectional view,

Fig. 4 is a fragmental perspective view of one of the walls broken to expose the construction.

Referring in detail to the drawings by numerals 1 designates as an entirety, the protector which is a box like construction having the side walls 2, a bottom 3, top 4 and end walls 5 each of which is provided with a door 6.

The sides, top and bottom are substantially of the same construction and each comprises four thicknesses or layers of material. The inner thickness is composed of a plurality of longitudinally arranged planks or strips 7 which are placed in close contact with each other. The next layer or thick-

ness consists of a plurality of planks or strips 8 arranged in close contact with each other and running diagonally across the strips of the inner layer. The next thickness consists of a plurality of planks or strips 8', arranged diagonally with respect to the inner strips and running transversely of the second layer. The outer layer or thickness is formed by closely arranged strips 9 running at right angles to the strips 65 of the inner thickness.

The strips of one thickness may be secured rigidly to the strips of the next thickness by any desired means such as nails or bolts, and the three inner thicknesses of the top 70 and bottom are preferably disposed between the sides to abut thereagainst as shown. The strips of the outer thicknesses on the sides extend above and below the strips forming the three inner thicknesses of the 75 sides and between these extended portions are arranged the outer thicknesses of the top and bottom. This peculiar arrangement provides a construction which is absolutely rigid and which will withstand most any 80 shock or pressure.

The end walls 6 are preferably formed of only two layers or thicknesses of material, but the strips 10 and 11 forming these thicknesses are double the thickness of the strips 85 used in the construction of the sides, top and bottom. Each end wall is provided with a door opening 12 which is closed by a door 6 constructed of two layers of strips, 13 and 14, said strips being of the same thickness as 90 those employed in the construction of the end walls.

To provide for the comfort and convenience of the person or persons using this protector, a seat 14 running along one side 95 from end to end is provided, and at intervals along this seat are disposed hand holds 15. Above the seat and on the opposite side of the structure I employ a longitudinal brace rod 16 secured at its extremities in the 100 end walls and with its center held in position by eye bolts 17. This rod provides for additional hand holds and may be used by the occupant to steady himself.

A bumper or bumpers 18 are secured to 105 each side and to the top, to protect the structure when it collides with any object, and these bumpers run transversely to the length of the outer strips to which they are secured and brace the same. They have fur- 110

ther use in that they make it easier for the protector to be righted in case it should fall over. The doors have each an upright bumper, and the bottom may be equipped 5 with feet 19. Ventilating openings 20 suitably covered by the gratings 21 may be employed to give plenty of fresh air to the user of the contrivance.

Next inside the end walls and secured in 10 close contact with them are right-angular triangular braces 25, the hypotenuse of each crossing the door opening as best seen in Fig. 2 and forming a stop against which the door strikes when it closes. These braces 15 are particularly useful for preventing collapse of the structure in case it should be struck by an extraneous object or in case it should be tumbled about by the wind, whereas the seat 14' and the brace rod 16 run 20 from end to end and prevent longitudinal collapse, and the bumpers which for the most part cross the outside strips prevent them from being broken in by a tree or the like which might fall upon the structure. 25 It will be seen that I have taken ample precaution to protect the user from injury either by collapse of the structure or by crushing in from the outside.

From the foregoing description taken in 30 connection with the accompanying drawings it will be apparent that I have provided a very strong and rigid cyclone protector which is in no danger of collapsing due to pressure and shocks and which will guard 35 the occupant from the effects of a cyclone.

If desired, a rubber roofing may be secured to the top of the cyclone protector and extended down the sides and ends from two to three inches, and to better preserve the 40 device, it should be painted. A felt cover

for the seat may also be provided if thought desirable or necessary.

While I have shown and described the further embodiments of my invention, it will be understood that minor changes in 45 construction may be made without departing from the scope and spirit of the invention as claimed.

What is claimed is:—

1. The herein described cyclone protector 50 comprising a box-like structure whose walls, top, and bottom are formed of a plurality of thicknesses, each thickness consisting of strips disposed edge to edge and running at an angle to those in the next thickness the 55 strips in the outside thickness of each panel running transverse to the length of that panel, and bumpers secured to the outer faces of said panels and running longitudinally thereof.

2. The herein described cyclone protector comprising a box-like structure whose end walls have door openings, doors therein, an internal seat secured to one side wall and running from end to end, an internal brace rod opposite said seat and connected at its extremities with the ends, and eye-bolts connecting this rod between its ends with the other side wall.

3. The herein described cyclone protector 70 comprising a box-like structure having door openings in its ends, right-angular triangular braces secured in the corners of the structure against said ends and with the hypotenuse of each crossing a corner of the 75 opening therein, and a door movably mounted in each opening and contacting with said braces when closed.

In testimony whereof I affix my signature.

JACKSON L. ROY.
